UNITED STATES PATENT OFFICE.

AUGUSTIN HUBERT, OF BOSTON, MASSACHUSETTS.

BICYCLE-PADLOCK.

SPECIFICATION forming part of Letters Patent No. 511,430, dated December 26, 1893.

Application filed June 6, 1893, Serial No. 476,755. (No model.)

To all whom it may concern:

Be it known that I, AUGUSTIN HUBERT, a subject of the Queen of Great Britain, residing at Boston, in the county of Suffolk and State of Massachusetts, have invented a new and useful Improvement in Bicycle-Padlocks, of which the following is a specification.

This is a padlock especially adapted and intended for use in securing one of the cranks of a bicycle to the frame or stationary portion of the machine, whereby the crank is prevented from revolving, and hence the machine is prevented from being trundled off or removed in any manner unless it is taken up bodily.

The nature of the invention is fully described below, and illustrated in the accompanying drawings, in which—

Figure 1 is a side elevation of a portion of a bicycle with my padlock in position thereupon. Fig. 2 is a side elevation of my improved padlock closed. Fig. 3 is a similar view of the same open.

Similar letters of reference indicate corresponding parts.

A represents a portion of one of the wheels of a bicycle.

C is a portion of the driving chain, D E portions of the frame or stationary part of the machine, and F the cranks actuated by the treadles F' all constructed as usual.

My padlock is especially adapted to secure one of the cranks F to the portion E of the frame, such portion being usually circular in cross section.

H represents the case holding the lock, which is constructed in any well known manner, and h represents the key in position. The bow or hasp in a padlock is usually made in the form of a loop which is roughly on the lines of a half-circle.

In this invention, the bow or hasp is made in two parts. The part I is hinged at I' to the case, and describes a double curve of approximately ogee shape, and its free end, I'', is grooved preferably in a V shape. The part K is similar in shape to the part I, and is pivoted centrally thereto at L, suitable depressions l being made in the parts next the pivots for the sake of convenience. The outer

or free end K'' of the part K is preferably made in reverse V shape so as to fit into the V shaped portion I'' of the part I. The inner end K' is of suitable shape to engage a bolt in the lock. The parts I K are provided near their inner ends with inwardly projecting stops or buffers P, as shown.

When the hasp is closed as shown in Fig. 2, the two parts constitute two loops, presenting the appearance of a figure 8. The outer loop, being nearly circular, clasps around the portion E of the frame, while the inner loop incloses the crank F. When the hasp is closed, the parts P bear against each other so that the severe strain which the hasp may have to sustain will not be communicated to the lock, but will be sustained by the hasp itself by means of these projections or buffers P, which essentially relieve the lock. The outer jaws, by means of the V shape above described, fit together when closed, and are thus prevented from being bent or pulled apart laterally. The two loops, as will readily be seen, effectually prevent any material play of the crank, or movement, with relation to the frame E, in this respect possessing a decided advantage over a padlock with a single loop or bow large enough to inclose both the crank and frame. Moreover, when the hasp is closed, it is practically one integral hasp, inasmuch as the parts P P and I'' K'' touch and fit so that there can be no relative movement or play in the parts I K.

Having thus fully described my invention, what I claim, and desire to secure by Letters Patent, is—

1. The herein described improved bicycle padlock, comprising the lock, the doubly curved portion I of the hasp hinged at I' to the case and the doubly reverse curved portion K of the hasp adapted to engage with the lock, the said portions I and K being hinged together centrally at L and constituting when locked two closed loops of approximately the shape of a figure 8 adapted to inclose respectively a crank and a portion of the frame of the bicycle, substantially as set forth.

2. In combination, the doubly reverse curved portions I and K centrally hinged to

gether at L as shown, said portions when closed being approximately the shape of a figure 8, the portion I being hinged to the case of the lock and the portion K engaging the lock, the said portions I and K being provided near their inner ends with the two inward projections or buffers P bearing against

each other when the hasp is closed, substantially as described.

AUGUSTIN HUBERT.
